UNITED STATES PATENT OFFICE.

HENRY ERNEST MASSMANN AND WILLIAM RICHARD TINDALL, OF BRISTOL,
ENGLAND.

APPARATUS FOR FINISHING OR POLISHING CYLINDRICAL SURFACES.

1,111,482.

Specification of Letters Patent. Patented Sept. 22, 1914.

Application filed June 20, 1914. Serial No. 846,314.

To all whom it may concern:

Be it known that we, HENRY ERNEST MASSMANN and WILLIAM RICHARD TINDALL, both subjects of the King of Great Britain, 5 residing at 26 New Station road, Fishponds, Bristol, in the county of Gloucester, England, have invented certain new and useful Improvements in Apparatus for Finishing or Polishing Cylindrical Surfaces, of 10 which the following is a specification.

This invention relates to an improved apparatus for finishing or polishing internal cylindrical surfaces of cast iron, cast steel and other non-ductile metals, and is primarily intended for finishing or polishing the 15 internal surfaces of the cylinders of internal combustion and other high speed engines, and also cylinder liners or the like, in which a highly finished or polished surface and an 20 exact and uniform diameter are essential.

The chief object of the present invention is to dispense with the comparatively costly and lengthy operation of grinding and lapping, thereby overcoming certain disadvantages and objections, which occur with such 25 operations.

According to this invention instead of grinding or lapping a rough internal cylindrical metal surface such as is left after casting or rough drilling, a polished surface is 30 obtained by means of a roller tool which is placed within the cylinder or work and then set so as to be in contact with the internal surface without expanding or compressing 35 the metal and then causing relative rotation and longitudinal movement or reciprocation between the tool and the work to take place.

The minute roughened surfaces are worn 40 away by friction, and the action may be said to resemble that which takes place as a result of a rotary piston working longitudinally in the cylinder as distinct from the expanding or compressing action which takes place when a tool of larger diameter than the bore 45 of a metal tube is rotated while being forced through the tube, or when a roller tool is rotated and simultaneously caused to expand to compress or consolidate the internal surface being treated.

50 Further according to our invention we may provide suitable cutters in combination with the roller tool which cutters remove any irregularities in the surfaces that might prevent the movement of the tool within 55 the cylinder. One of the advantages of the

said longitudinal rolling action is that the pores of the metal are closed, and furthermore there is a complete absence of emery or carborundum dust, lead particles, sand and other materials which are used in the ordinary grinding and lapping operations. The rolling action is also advantageous in that it does not generate heat to the same extent as occurs in the usual grinding and lapping operations and consequently distortion of the 60 article caused by the subsequent cooling is less likely to take place.

The apparatus or tool which we may employ for carrying out this method may comprise, a number of rollers rotatably mounted 65 on slides which can be adjusted radially by a central conical or tapered member, operated by a rotary device on the tool body containing the said slides, the adjusting device being of less cross sectional area than the 70 area contained within the circular path traversed by the rollers. Suitable cutters may be used in combination with the rollers and are adjusted to remove inequalities in the internal surface under treatment, on being moved through the cylinder.

In order that the said invention may be clearly understood and readily carried into effect, it will now be described more fully with reference to the accompanying drawings, in which:

Figure 1 is an elevation (partly in section) of one form of the improved apparatus. Fig. 2 is a sectional plan view taken on the line 2-2 of Fig. 1, and Fig. 3 is a 90 sectional elevation taken on the line 3-3 of Fig. 2.

a is the spindle or body portion of the tool shaped at one end *a'* (see Fig. 3) to engage with or fit into any appropriate chuck or 95 holder forming part of a rotary machine and provided with a box or casing *a²* at its other end; *b b b* represent three radial slides which are slidably mounted in guides *a³* forming part of a box or casing so as to be 100 readily adjustable. *c c c* represent the hardened rollers which are rotatably carried by the radial slides.

In the example shown each of the rollers is barrel shaped and is mounted to rotate 105 freely on a pin *c'* secured in any appropriate manner to the slide *b*; ball bearings may be provided as shown at *c²* and *c³*. A cutter *c⁴* may be rigidly secured to the outer end of the roller so as to rotate therewith. The 110

radial adjustment of the slides is in the example shown effected by the central member or stem d arranged within the body a and provided with a conical end d' which 5 engages with inclined curved faces on the ends of the said slides b . The upper end of the stem is provided with a cross piece d^2 which at its extremities projects through oppositely disposed longitudinal slots a^4 in 10 the body a ; a coil spring d^3 surrounding the stem is interposed between the cross piece d^2 and a collar or bush d^4 fixed within the spindle a to permit the stem to be longitudinally moved or adjusted.

15 A portion of the exterior of the spindle is screw threaded to receive a nut e which at its lower part is adapted to engage with rollers d^5 carried on the extremities of the cross piece d^2 of the stem d . Thus when 20 the nut is adjusted or angularly displaced in one direction it bears upon the cross piece and forces the stem downwardly against the action of the spring thereby adjusting the radial slides and the rollers carried thereby 25 outwardly by the action of the conical end of the stem and the inclined inner faces of the slides b . When the nut is adjusted or angularly displaced in the opposite direction the spring pushes the cross piece in the 30 opposite longitudinal direction thus allowing the slides to be moved inwardly. The upper part of the nut is provided with a beveled annular face e' which is marked with graduations or a scale, the said scale 35 being adapted to register with a fixed point or marking e^2 on the spindle, so that any desired adjustment can easily be obtained by setting a given graduation or the scale against the marking e^2 .

40 In operation, the tool is held on or connected to any suitable rotary shaft by means of a chuck or the like and when the tool is positioned within the cylinder (the internal surface of which is to be finished or polished) and the nut adjusted to move the 45 rollers into contact with the internal periphery of the cylinder, the shaft and tool are caused to rotate. During the rotation of the tool around its longitudinal axis the 50 rollers bearing against the internal cylindrical surface are caused to rotate on their own respective pins, and thus the cutters are caused to rotate and remove inequalities on the surface. Owing to the simultaneous 55 longitudinal movement and reciprocation which is imparted to the tube the whole of the internal peripheral surface is subjected to the action of the rollers and the cutters.

What we claim and desire to secure by 60 Letters Patent of the United States is:—

1. Apparatus for finishing and polishing

internal cylindrical surfaces comprising in combination, a casing or body having an enlarged lower portion, radially movable slides mounted in said enlarged portion, 65 rollers carried by said slides, a longitudinally movable adjusting member having a tapered end in contact with said slides for moving the same, a cross-head carried by said member, resilient means for forcing 70 said adjusting member in one direction, and a rotating means threaded on said casing in contact with said cross-head for moving said adjusting member in an opposite direction. 75

2. Apparatus for finishing and polishing internal cylindrical surfaces comprising, in combination, a casing or body having an enlarged lower portion, radial slides movably mounted in said portion, a roller and cutter rotatably carried by each slide, a longitudinally movable adjusting member having a tapered end in contact with said slides for moving the same, said adjusting member having a cross-head on its end opposite the tapered portion, resilient means bearing 80 against said cross-head for moving the adjusting member in one direction, a rotating member threaded on said body in contact with said cross-head to move the adjusting member in an opposite direction, and a scale 85 of graduations on said rotating member adapted to coöperate with a fixed point on said body. 90

3. An apparatus for finishing and polishing internal cylindrical surfaces, comprising in combination a casing or body having an enlarged lower portion, radial slides movably mounted in said portion, a cutter and roller rotatably carried by each slide, a longitudinally movable adjusting member having a tapered end in contact with said slides for moving the same, a cross-head on 95 said adjusting member, a spring within the casing bearing at one end against the cross-head for retracting the adjusting member from the slides, a sleeve within the casing adapted to be longitudinally adjusted therein and bearing against the opposite end of the spring whereby to vary the tension of the spring, and a rotating member threaded 100 for adjustment on said body and adapted for engagement with said cross-head whereby to project the adjusting member against said slides. 105

In testimony whereof we affix our signatures in presence of two witnesses. 110
